UNITED STATES PATENT OFFICE.

ISAAC NOAR, OF NEW YORK, N. Y.

NECKSCARF.

SPECIFICATION forming part of Letters Patent No. 289,356, dated November 27, 1882.

Application filed September 5, 1883. (No model.)

To all whom it may concern:

Be it known [that I, ISAAC NOAR, a citizen of the United States, residing at New York, in the county of New York and State of New York, have invented certain new and useful Improvements in Neckties; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a perspective view. Fig. 2 is a front view of the back portion of the shield. Fig. 3 is a plan view of the front portion of the shield. Fig. 4 is a top view of the spring-jaws. Fig. 5 is a section, and Fig. 20 6 is a perspective view, of the same.

This invention has relation to neckscarfs; and it consists in the construction and novel arrangement of devices, as will be hereinafter fully described, and particularly pointed out in the claims appended.

Referring by letter to the accompanying drawings, *a* designates the rear or base portion of the shield of the neckscarf, which is of flannel stiffening or other suitable textile fabric, instead of the pasteboard heretofore employed. Two pairs of clamping spring-jaws or clamps of metal are joined at their inner ends by a rivet or otherwise, one being in nearly a horizontal position out to about the 35 edge of the back portion of the shield, and the other arm, *b'*, extending upwardly at an angle of about forty-five degrees from the arm *b*. The arms *b b'* of the spring-jaws are perforated at *c c* near their edges, and are stitched to the 40 front of the back portion, *a*, of the shield, as shown in the drawings. The arms *b b'* of the spring-jaws extend along the shield *a* until near the edge on one side and near to the upper corner at the opposite side, where they are 45 bent forward away from the face of the portion *a*. These inclined portions *e e* of the arms *b b'* are provided each with a rectangular slot, *f*, and their extremes are curved rearwardly at *g*, and are serrated. The spring-arms *h h'* 50 are secured to the arms *b b'*, and are bent or inclined outwardly or forward therefrom for a portion of their length, and are there reduced in size, as at *i*, bent rearwardly, and passed through the rectangular slots *f*. These arms *h* and *h'* are slitted for a portion of their length 55 on their under side, as shown at *t* in Fig. 5, to form a spring for the engagement of the serrated jaws. The reduced ends of these arms are provided with short forwardly-curved serrated plates *k*, which in their normal positions 60 engage the serrations of the plates opposite them. The spring-jaws near the corner of the shield are to clamp and hold the end of the neck-strap, so that it need not be stitched in place. The spring-jaws near the opposite 65 lower edge are to receive and hold the neck-band after it has been passed around the neck of the wearer. The front portion, *l*, of the shield is also of flannel or other suitable fabric, instead of pasteboard. To this portion is 70 stitched the material that forms the front of my flat neckscarf. The central or middle strip, *m*, is first stitched in place, and is of a different color from the body of the front, and with the aid of the pointed piece *n* meeting 75 across the tapering middle piece a contrast of color is produced, which imparts a very nice appearance. The shield portion *l* is stitched to the portion *a* in such a manner that the side edges at the spring-jaws will be left open 80 for the introduction of the neck-strap to the jaws, which is accomplished by pressing the spring-jaws below the slots between the thumb and finger, and entering the neck-strap from the side, instead of passing it down through 85 the shield, as was formerly practiced. This saves the steel point for the neck-strap, and the silk that covers it does away with the pasteboard, and also with the pin that was employed to hold the neck-strap in place 90 around the neck, and prevents it injuring the maker's or user's fingers. The spring-jaws and their several arms hold the shield in shape. The eyelet for the collar-button depends from an elastic secured between the shield portions 95 *a* and *l*, and is of the ordinary form.

In this construction there is a great deal of labor saved by making the central strip a portion of the scarf, the center piece heretofore used requiring extra labor and extra material—viz., silk, flannel, and lining—and also the crossing of the point-pieces.

Having thus fully described my invention, what I claim as new, and desire to secure by Letters Patent, is—

1. In a neckscarf, the spring-arms connected at their adjacent ends, and stitched to the shield, as shown, to form a stiffener for the same, the said arms having serrated clamping ends to receive the neckband and the shield secured to the tie, substantially as specified.
- 10 2. The spring-arms consisting of the parts *b* and *b'*, having a rectangular slot, *f*, the arms *h* and *h'*, having a reduced portion, *i*, to pass through the said slots, and a slotted bent portion, *t*, to form a spring for the same, both arms having bent serrated clamping ends, and adapted to be secured together and to the shield of a tie, substantially as and for the purposes specified.
- 15 3. In a neckscarf, the front portion con-

structed with its middle portion of a different 20 color from the body, and having the point-pieces meeting over the middle strip, substantially as specified.

4. In a neckscarf, the combination, with the shield *a*, of the spring-jaws consisting of 25 the horizontal arm *h* and the angular arm *h'*, connected together, and each having a bent slotted and serrated portion, and the reduced portion *i*, passing through the slots, and provided with serrated plates at their ends, substantially as specified.

In testimony whereof I affix my signature in presence of two witnesses.

ISAAC NOAR.
